UNITED STATES PATENT OFFICE

112,732

DESIGN FOR A TEXTILE FABRIC

Herman Blum, Philadelphia, Pa.

Application November 19, 1938, Serial No. 81,243

Term of patent 3½ years

To all whom it may concern:

Be it known that I, Herman Blum, a citizen of the United States, residing at Philadelphia, in the county of Philadelphia and State of Pennsylvania, have invented a new, original, and ornamental Design for a Textile Fabric, of which the following is a specification, reference being had to the accompanying drawing, forming part thereof.

The drawing shows a plan view of a textile fabric showing my new design.

I claim:

The ornamental design for a textile fabric, as shown.

HERMAN BLUM.
